[57] **CLAIM**

The ornamental design for a light fixture, as shown and described.

DESCRIPTION

FIG. 1 is a front elevational view of a lighting fixture of FIG. 1;

FIG. 2 is a right side elevational view of the lighting fixture of FIG. 1;

FIG. 3 is a rear elevational view of the lighting fixture of FIG. 1;

FIG. 4 is a rear elevational view of the lighting fixture of FIG. 1;

FIG. 5 is a top plan view of the lighting fixture of FIG. 1; and,

FIG. 6 is a bottom plan view of the lighting fixture of FIG. 1.

The stippling shown in the figures is for shading purposes only, and does not form a part of the claimed design. The broken lines showing the glass lampshade are for illustrative purposes only and forms no part of the claimed design.
